FIG. 6.

UNITED STATES PATENT OFFICE.

CHARLES H. KOEHLER, OF CHICAGO, ILLINOIS, ASSIGNOR TO EFFICIENCY MILEAGE RECORDER CO., OF HIGHLAND PARK, KENTUCKY, A CORPORATION OF KENTUCKY.

ELECTRICAL CONTROL APPARATUS.

1,358,082.

Specification of Letters Patent.

Patented Nov. 9, 1920.

Application filed October 29, 1919. Serial No. 334,251.

To all whom it may concern:

Be it known that I, CHARLES H. KOEHLER, a citizen of the United States, residing in Chicago, county of Cook, and State of Illinois, have invented certain new and useful improvements in Electrical Control Apparatus, of which the following is a specification.

My invention relates to electrical apparatus for effecting electrical operations, as indication, recording, counting, etc., proportional to the number of revolutions of the wheels of a vehicle and particularly of an electrically propelled railway car.

My invention resides in electrical circuit controlling apparatus operated by the vehicle axle and applied upon the end thereof within the journal box or housing.

My invention resides also in a system of the character referred to wherein the electro-responsive means is in such wise related to the electrical circuits of an electrically operated railway car that there is impressed thereon suitably reduced voltage.

For an illustration of some of the various forms my invention may take, reference is had to the accompanying drawings, in which:

Figure 1 is a side elevational view of the circuit controlling mechanism.

Fig. 2 is a sectional view of the same taken on the line 2—2 of Fig. 1.

Fig. 3 is a side elevational view of the structure shown in Fig. 1 with parts removed and showing the contacts in different position.

Fig. 4 is a top plan view of the end of a car journal or axle having my circuit controlling mechanism applied thereto.

Fig. 5 is a front elevational view of the same.

Fig. 6 is a diagrammatic view illustrating a control system in which the aforesaid voltage reduction is obtained, and illustrating a mode of application of my circuit controlling mechanism.

Referring to Fig. 1, A is a stationary circular cupped member extending through a circular opening in the rotary metal ring member B having the counterbore b receiving the flange a of the metal member A. Holding the member A in operative position within the ring B is the back plate C having holes registering with the holes c through

the ring member B, screws d, Fig. 5, extending through the holes in members B and C and securing them to the end of the car axle or journal J concentric therewith.

Extending through the member A at its center is the collar e of a stud f extending through an axial hole in the member C and upon which is threaded the nut g whereby the stud f and its collar e are secured to the plate C. Extending into the cavity or cup of the member A is the cam h integral with or secured to the collar e and stud f, and rotating therewith. A bracket i is secured by screw j upon the bottom of the ring member A within its cavity or recess. Secured upon the bracket i is the yielding or spring member k constituting a contact arm actuated by the cam h and having a bias for movement in such direction as to separate the contact l at the end of the arm k, as indicated in Fig. 1, away from the co-operating stationary contact m carried upon the resilient or yielding stationary contact arm n insulated from member A and secured at o upon the inner end of the member p secured upon member A and preferably of insulating material. Extending through the member p is a conductor q in electrical communication with the contact arm n. The conductor q is connected exteriorly to the member p with a flexible insulated conductor r terminating in a metallic clip structure s comprising the member t having a hole u, and a resilient hook-shaped member v longitudinally slotted to receive the member t. This form of clip terminal is preferred, though not essential, because under the conditions of jar attendant upon railway or similar traffic it maintains satisfactory electrical connection with the remainder of its circuit and partakes of the jar and vibration without breakage of connection with the insulated conductor r and prevents rupture of that conductor due to continued vibration.

A closing cap D is held by screws w to the ring member A and is provided with a channel-shaped radially extending arm x which shields or covers the member p and serves to prevent rotation of the member A and its attached parts when the member B is rotating with the axle J.

Referring now more particularly to Figs. 4 and 5, the structure hereinbefore described is shown secured upon the end of the axle

or journal *J* disposed within the journal box or housing *H* having the usual closing lid, not shown, which may be hinged, for example, in the lugs *y*.

Extending through an insulating bushing *z* in a wall of the journal box *H* is a bolt *a*¹ on whose outer end is threaded the nut *b*¹ between which and the wall of the box *H* intervenes an insulating washer *c*¹. On the inner end of the bolt *a*¹ is the nut *d*¹, under which is disposed the insulated washer *e*¹, between which and the inner wall of the journal box *H* is secured the member *f*¹ having the two inwardly extending arms *g*¹ and *h*¹ having at their ends inwardly turned pins or extensions *i*¹ and *j*¹, between which is received the aforesaid arm *w* of the cover plate *D* on the member *A*, whereby the member *A* is held against rotation notwithstanding rotation of the ring *B* with the axle and journal *J*.

Car axles partake of end play, and to allow for such end play the pins or inward extensions *i*¹ and *j*¹ are provided, of suitable length that for all possible positions during end play of the journal *J* the member *w* will always be held between the pins or extensions to prevent rotation of the member *A*, the arm *w* playing backwardly and forwardly longitudinally between the pins *i*¹ and *j*¹.

On the inner end of the bolt *a*¹ is a post or pin *k*¹ received in the hole *u* of the terminal clip upon the conductor *r*, the spring hook end *v* securely holding the clip to the pin or post *k*¹. At its outer end there is held to the bolt *a*¹ by the nut *m*¹ the terminal *n*¹ of a conductor in the circuit controlled by the contact mechanism described.

The bolt *a*¹ performs the dual function of forming an electrical connection with the flexible conductor *r* of the contact mechanism and of securing in position the pins or members *i*¹ and *j*¹ for allowing end play and yet preventing rotation of the member *A* and its attached parts. The arm or equivalent in coöperation with the pins *i*¹ and *j*¹, or equivalent structure, permits also variation in distance vertically of the axle or journal *J* with respect to the journal or bearing structure, in that, after considerable wear of the journal brasses, new brasses may be inserted without effect upon the co-operation of the arm *w* with pins *i*¹ and *j*¹. That is to say, the structure described is independent of bearing wear or bearing replacement.

In Fig. 6 there is shown an arrangement of electrical circuits in which the above described contacting mechanism is utilized. *F* represents a trolley wire, third rail or other contact conductor in connection with the feeder system or generator of an electric railway system. With the conductor *F* engages the traveling contact *W*, as a trol-

ley wheel, contact shoe or the like, carried by the car driven by the electric motor comprising the armature *E* and field winding *S* in a circuit between the trolley wheel *W* and the track or return rail *R* through any suitable railway motor controller indicated herein at *G*. When the controller *G* is in position to energize the motor *ES*, current may pass from the wire *F*, through trolley wheel *W*, controller *G*, and a resistance unit *o*¹, of, for example, 2000 ohms on a 600 volt system, and coil *p*¹ of a relay to the track or earth return *R*. This will cause attraction of the relay armature *q*¹, in opposition to spring *r*¹, against the front contact *s*¹, whereby current can flow, independently of the controller *G*, from wire *F*, contact wheel *W*, through resistance unit *t*¹ to earth or track return *R*. The total resistance of the unit *t*¹ may be, for example, 10,000 ohms, of which about three-fourths is comprised between its terminal *u*¹ and the connection *v*¹, and about one-fourth between the connection *v*¹ and its lower terminal *w*¹, the relay armature *q*¹ being in communication with the aforesaid connection *v*¹. By this arrangement the full voltage of the power circuit is not operative in the circuit controlled by the relay armature or tongue *q*¹, but only about one-fourth of the total voltage is so operative, it being understood, however, that any suitable fraction of the entire voltage may be employed, though a small fraction is preferred. When the relay winding *p*¹ is deenergized, as when the circuit through the motor *ES* is open, the spring *r*¹ retracts the relay tongue *q*¹ against the back contact *w*¹. The relay contacts *s*¹ and *w*¹ are connected, respectively, with terminals of electro-magnets whose coils are *y*¹ and *z*¹, whose other terminals connect with conductor *a*² whose terminal is *n*¹, above described, in communication with the bolt *a*¹, and through it with the conductor *r* and the contact arm *n* of the contact mechanism of which the contact arm *k* is in electrical communication with the earth or track return *R* through the metallic members *A*, *B* and the axle *J* and the car wheel, not shown. The electro-magnets *y*¹ and *z*¹, or either of them, may be utilized for any suitable purpose. Here they are shown as coöperating with their armatures *b*² and *c*² of step-by-step counters, indicators or recorders *d*², *e*², which may, for example, record or indicate the mileage traveled by the car on which it is carried.

The operation is as follows:

As the carwheel travels along the track or rail its axle or journal *J* rotates, thereby rotating the ring *B* and plate *C*, the latter carrying the cam *h* which accordingly rotates with the car wheel, the stud *f* and the cam *h* being coaxial with the journal *J* and the car wheel. The member *A* is prevented from rotation as described, and therefore

the members B and C in effect rotate upon the stationary member A. As a result the cam h rotates with respect to the contact arm k periodically bringing its contact l into engagement with the contact m upon the contact arm n in electrical communication with the conductor r which may form part of any suitable circuit for any control, indicating or other purpose.

10 When the cam h passes out of engagement with the arm k, the latter, due to its bias, separates the contact l from contact m, thereby rupturing the circuit, which is not again closed until the cam h reengages the arm k. By the mechanism described, therefore, there is for each revolution of the car axle J an engagement of the contacts n and m with each other and closure of circuit between trolley wire F and track or return 15 rail R through one or the other of the magnets y¹ or z¹, depending upon the position of the relay tongue q¹, which in turn is dependent upon whether or not the electric motor ES is energized and driving the car.

20 Accordingly the indicator or recorder d² will be operative only when the car is being driven by the motor, while the recorder or indicator e² will be operated only when the power is off and the car coasting.

25 The cam h or equivalent means for actuating the movable contact may be of either conducting or insulating material. When of conducting material, as for example steel, it serves by engagement with the contact arm k to effect, independently of the bracket structure i and member A, a low resistance 30 connection with the axle or journal J, as through the members C and B.

What I claim is:

- 40 1. In a system of the character described, the combination with a power circuit, of a car driving motor, circuit controlling mechanism operated a number of times dependent upon the distance traveled by the car, a 45 resistance connected across said power circuit, a circuit tapped off a part of said resistance controlled by said circuit controlling mechanism and independent of said motor, recording or indicating mechanism, 50 and a winding in said last named circuit controlling said last named mechanism.
2. In a system of the character described, the combination with a power circuit, of a car driving motor, circuit controlling mechanism operated a number of times dependent 55 upon the distance traveled by the car, a resistance connected across said power circuit, a circuit including said circuit controlling mechanism and a fraction of said resistance, 60 said circuit having branches including electro-responsive means, recorder or indicator mechanism controlled by each of said means, and electro-responsive means bringing said branches respectively into circuit as said 65 motor is or is not energized.

3. The combination with a car axle, of circuit controlling mechanism actuated by said axle and comprising a ring member secured upon the end of said axle and rotating therewith, of a stationary annular member coaxial with said axle, fixed and movable contacts carried by said stationary member, and means carried by said ring member for moving said contacts with respect to each other. 70

4. The combination with a car axle, of circuit controlling mechanism comprising relatively rotatable coaxial members, means securing one of said members upon the end of said axle coaxial therewith, contact members carried by the other of said members, 75 means carried by said one of said members causing movement of said contact members with respect to each other, and means for preventing rotation of said other of said members. 80

5. The combination with a car axle, of circuit controlling mechanism comprising relatively rotatable coaxial members, means securing one of said members upon the end of said axle coaxial therewith, relatively movable contacts carried by the other of said members, means rotating with said one of said members moving said contacts with respect to each other, an arm secured to said other of said members, and stationary means 90 preventing rotation of said arm. 95

6. The combination with a car axle having end play, of circuit controlling mechanism comprising relatively rotatable coaxial members, means securing one of said members upon the end of said axle coaxial therewith, relatively movable contacts carried by the other of said members, means rotating with said one of said members moving said contacts with respect to each other, an arm secured to said other of said members, and stationary means 100 preventing rotation of said arm. 105

7. The combination with a car axle, of circuit controlling mechanism comprising a member secured upon the end of said axle, another member within said first named member and with respect to which said first named member is rotatable, said members 110 being in electrical communication with each other and said axle, relatively movable contacts carried by said other of said members, a cam carried by said one of said members for actuating said contacts, a member of insulating material carried by said other of said members preventing rotation thereof and carrying one of said contacts, the other of said contacts connected with said other 115 of said members. 120

8. The combination with a car axle and a journal box, of circuit controlling mechanism housed within said box comprising coaxial members rotatable with respect to each other, one of said members secured to the 125 130

end of said axle, the other of said members carrying relatively movable contacts one of which is in electrical communication with said axle, means supporting the other of 5 said contacts upon and insulating it from said other of said members, means rotatable with said one of said members for moving said contacts with respect to each other, an arm attached to said other of said members, 10 and means carried by said journal box for preventing rotation of said arm.

9. The combination with a car axle and a journal box, of circuit controlling mechanism housed within said box comprising coaxial members rotatable with respect to 15 each other, one of said members secured to the end of said axle, the other of said members carrying relatively movable contacts one of which is in electrical communication 20 with said axle, means supporting the other of said contacts upon and insulating it from said other of said members, means rotatable with said one of said members for moving said contacts with respect to each other, an arm attached to said other of said members, 25 and means carried by said journal box preventing rotation of said arm and allowing movement thereof with end play of said axle.

30 10. The combination with a car axle and a journal box, of circuit controlling mechanism housed within said box comprising coaxial members rotatable with respect to each other, one of said members secured to 35 the end of said axle, the other of said members carrying relatively movable contacts one of which is in electrical communication with said axle, means supporting the other of said contacts upon and insulating 40 it from said other of said members, means rotatable with said one of said members for moving said contacts with respect to each other, an arm attached to said other of said members, means carried by said journal box 45 for preventing rotation of said arm, and an electrical connection to said circuit controlling mechanism through a wall of said journal box.

11. The combination with a car axle, of 50 circuit controlling mechanism comprising a member secured upon the end thereof, a second member coaxial with said axle and having a bearing within said first named member, said second member having a cavity, a 55 contact within said cavity in electrical communication with said axle, a coöperating contact supported upon and insulated from said second member within said cavity, means movable with said first named member for moving said contacts with respect 60 to each other, a cover member secured to said second member and having an arm, a connection with the other of said contacts supported by said arm, and means for preventing rotation of said arm. 65

12. The combination with a car axle, of circuit controlling mechanism comprising a member secured upon the end of said axle, a second member having a bearing for said first member coaxial with said axle, relatively movable contacts carried by said second member, means carried by said first named member rotating therewith for actuating said contacts with respect to each other, an arm secured to said second member, a member of insulating material associated with said arm secured to said second member and supporting one of said contacts, and means for preventing rotation of 70 said arm. 75

13. The combination with a car axle, of circuit controlling mechanism comprising a member secured upon the end of said axle, a second member having a bearing for said first member coaxial with said axle, relatively movable contacts carried by said second member, means carried by said first named member rotating with said first named member for actuating said contacts with respect to each other, an arm secured to said second member, a member of insulating material associated with said arm secured to said second member and supporting one of said contacts, means for preventing rotation of 80 said arm, a flexible connection extending to said member of insulating material, a journal box supporting said means preventing rotation of said arm, and an electrical connection through a wall of said box to said 85 flexible connection. 90

14. The combination with a car axle having end play, of a journal box, circuit controlling mechanism housed within said box and comprising a member secured upon the 105 end of said axle, a member coaxial with said axle secured to said first named member and rotatable with respect thereto, circuit breaking and closing mechanism carried by said second member, means rotatable with said first named member for actuating said circuit breaking and closing mechanism, members supported by said journal box and extending substantially parallel with the axis 110 of said axle and angularly spaced from each other, and an arm secured to said second member held between said spaced members and partaking of longitudinal movement between said spaced members with end play of said axle. 115

15. The combination with a rotating shaft, of circuit controlling mechanism comprising relatively rotatable coaxial members carried by said shaft and one of which is secured upon and rotates with said shaft, an arm on another of said members, and means engaging said arm to prevent rotation of said other of said members. 120

16. The combination with a rotating shaft having end play, of circuit controlling mech- 130

- anism comprising relatively rotatable coaxial members one of which is secured upon the end of said shaft, an arm on another of said members, and means engaging said arm 5 to prevent rotation of said other of said members and allowing longitudinal movement of said arm during end play of said shaft.
17. The combination with a shaft and a journal box therefor, of circuit controlling mechanism comprising coaxial members rotatable with respect to each other and one of which is secured upon the end of said shaft, an extension on another of said members, 10 and means secured upon said journal box within the same engaging said extension to prevent rotation of said other of said members.
18. The combination with a shaft having end play and a journal box therefor, of circuit controlling mechanism comprising coaxial members rotatable with respect to each other and one of which is secured upon the end of said shaft, an extension on another 15 of said members, and means secured upon said journal box within the same engaging said extension to prevent rotation of said extension and allowing longitudinal movement thereof during end play of said shaft.
19. The combination with a rotating shaft, 20 of circuit controlling mechanism comprising relatively rotatable coaxial members carried by said shaft and one of which is secured upon and rotates with said shaft, an arm on another of said members, means engaging said arm to prevent rotation of said other of said members, and a circuit comprised in part of said shaft and controlled by said circuit controlling mechanism.
20. The combination with a rotating shaft having end play, of circuit controlling mechanism comprising relatively rotatable coaxial members one of which is secured upon the end of said shaft, an arm on another of 25 said members, means engaging said arm to prevent rotation of said other of said members and allowing longitudinal movement of said arm during end play of said shaft, and a circuit comprised in part of said shaft 30 and controlled by said circuit controlling mechanism.
21. The combination with a shaft and a journal box therefor, of circuit controlling mechanism comprising coaxial members rotatable with respect to each other and one of which is secured upon the end of said shaft, an extension on another of said members, means secured upon said journal box within the same engaging said extension to prevent 35 rotation of said other of said members, a circuit comprised in part of said shaft and controlled by said circuit controlling mechanism, and an electrical connection to said circuit controlling mechanism extending 40 through a wall of said journal box.
22. The combination with a rotating shaft, 45 of circuit controlling mechanism comprising a member carried by said shaft and rotating therewith, a second member carried by said first named member and rotatable relatively thereto, and means holding said second named member against rotation.
23. The combination with a rotating shaft, 50 of circuit controlling mechanism comprising relatively rotatable coaxial members carried by said shaft, one of said members fixed to and rotating with said shaft, the other of said members bearing on said one member and held against longitudinal movement relatively thereto, and means holding 55 said other member against rotation.
24. The combination with a rotating shaft having end play, of circuit controlling mechanism comprising relatively rotatable coaxial members carried by said shaft, one 60 of said members fixed to and rotatable with said shaft, the other of said members bearing upon said one member and held against longitudinal movement relative thereto, and means holding said other member against 65 rotation and allowing longitudinal movement thereof during end play of said shaft.
25. The combination with a car axle, of circuit controlling mechanism actuated by said axle comprising a ring member secured 70 upon said axle and rotating therewith, an annular member bearing on said ring member and held against longitudinal movement relatively thereto, and means holding said 75 annular member against rotation.
26. The combination with a car axle having end play and a journal box, of circuit controlling mechanism carried by said axle and housed within said box comprising members rotatable with respect to each other, 80 one of said members secured to said axle and rotating therewith, the other of said members bearing on said one member and held against longitudinal movement relative thereto, an arm on said other member, and stationary means carried by said journal box engaging said arm and preventing rotation thereof while permitting movement 85 thereof during end play of said axle.
27. The combination with a rotary shaft, 90 of circuit controlling mechanism comprising relatively rotatable coaxial members, one of which is secured upon the end face of said shaft, an arm on another of said members, and means engaging said arm to 95 prevent rotation of said other of said members.
28. The combination with a rotating shaft, 100 of a circuit controlling mechanism comprising relatively rotatable coaxial members carried by said shaft and one of which is secured upon the end face of said shaft, an arm on another of said members, and means engaging said arm to prevent rotation of 105 said other of said members.

29. The combination with a rotating shaft, of circuit controlling mechanism comprising a member secured upon the end face of said shaft and rotating therewith, a second member carried by said first named member and rotatable relatively thereto, and means holding said second named member against rotation.
30. The combination with a rotating shaft and a journal box therefor, of circuit controlling mechanism comprising a member upon the end of said shaft and rotating therewith, a second member bearing upon said first named member and rotatable relatively thereto, a projection on said second named member, and means on said journal box engaging said projection to prevent rotation of said second named member.
31. The combination with a car axle, of circuit controlling mechanism actuated by said axle comprising a ring member secured upon the end face of said axle and rotating therewith, an annular member bearing on said ring member and held against longitudinal movement relatively thereto, and means holding said annular member against rotation.
32. The combination with a car axle and a journal box therefor, of circuit controlling mechanism actuated by said axle comprising a ring member secured upon the end face of said axle and rotating therewith, an annular member bearing on said ring member and held against longitudinal movement relatively thereto, a projection on said annular member, and means on the wall of said journal box engaging said projection to prevent rotation of said annular member.

In testimony whereof I have hereunto affixed my signature this 28th day of October, 1919.

CHARLES H. KOEHLER.
